UNITED STATES PATENT OFFICE.

WILLIS F. WALKER, OF ALBURTIS, PENNSYLVANIA.

METALLIC TIE.

1,016,309.

Specification of Letters Patent.

Patented Feb. 6, 1912.

Application filed March 10, 1911. Serial No. 613,587.

To all whom it may concern:

Be it known that I, WILLIS F. WALKER, a citizen of the United States, residing at Al-
5 burtis, in the county of Lehigh and State
of Pennsylvania, have invented a new and
useful Metallic Tie, of which the following
is a specification.

This invention relates to composite rail-
way ties of that type utilizing a metallic
10 body and a plastic filling of concrete or the
like.

One of the objects of the invention is to
provide a tie having improved means for
anchoring the plastic material to the me-
15 tallic portion thereof, said metallic portion
being readily produced by rolling.

Another object is to provide novel means
for fastening rails to the tie, said fastening
means including bolts of peculiar construc-
20 tion readily shiftable into or out of engage-
ment with the tie and which permit any de-
sired adjustment of the rails toward or from
each other to vary the gage of the track.

With the foregoing and other objects in
25 view which will appear as the description
proceeds, the invention resides in the combi-
nation and arrangement of parts and in
the details of construction hereinafter de-
scribed and claimed, it being understood
30 that changes in the precise embodiment of
the invention herein disclosed can be made
within the scope of what is claimed with-
out departing from the spirit of the inven-
tion.

35 In the accompanying drawings, the pre-
ferred forms of the invention have been
shown.

In said drawings:—Figure 1 is a perspec-
tive view of one form of tie embodying the
40 present improvements, a rail being shown
secured to one end portion thereof. Fig. 2
is an enlarged side elevation of a portion of
the tie and showing, in section a rail secured
thereon, one of the rail engaging plates
45 being shown in section. Fig. 3 is a trans-
verse section through the tie and showing,
in elevation, the rail fastening means. Fig.
4 is a perspective view of one of the bolts
used for fastening a rail to the tie. Fig.
50 5 is a plan view of another form of tie hav-
ing the present improvements embodied
therein, a rail being shown fastened there-
on. Fig. 6 is a side elevation of a portion
55 of the tie, a rail being shown in section
thereon and secured thereto. Fig. 7 is a
transverse section through the tie showing

ing the rail fastening means in elevation.
Fig. 8 is a section on line A—B Fig. 5.

Referring to the figures by characters of
reference 1 designates the base of the me-
tallic body of the tie, this base being made
up of oppositely extending flanges ar-
ranged longitudinally along the lower edge
portion of an upstanding web 2 integral
with the base and provided, along its up-
per edge with longitudinally extending
flanges 3 constituting the head of the tie
body. These flanges 3 are preferably of less
width than the flanges 1 and each flange
1 and 3 has its outer longitudinal edge por-
tion curved, as indicated at 4, the curved
portions of the flanges 1 being extended up-
wardly while the curved portions of the
flanges 3 are extended downwardly, these
curved portions coöperating to constitute
anchoring means for holding a concrete fill-
ing 5 against displacement. This filling is
interposed between the flanges 1 and 3 and
fits against the web 2, the said filling being
located in the end portions of the tie and
partly or entirely filling that portion of the
tie located between the rails when fastened
thereon. Openings 6 are formed in the web
2 under those portions of the flanges 3
adapted to support the rails and these open-
ings 6 are preferably arranged in pairs.
Each opening is adapted to receive a fas-
tening bolt of novel form, said bolt includ-
ing a central cylindrical portion 7 the di-
ameter of which is slightly less than the
diameter of opening 6. This cylindrical
portion is provided with diverging arms 8
projecting from the ends thereof and said
arms have threaded terminal portions 9 ex-
tended along parallel lines. The length of
the cylindrical portion 7 is slightly greater
than the thickness of the web 2 and the di-
verging arms 8 are so proportioned that,
when the fastening bolt is seated within the
opening 6, these arms will extend upward to
100 points adjacent the longitudinal edges of
the flanges 3 and the threaded terminal por-
tions 9 project upwardly above these flanges,
as clearly shown in Fig. 3. The bolt may
be swung with the cylindrical portion 7 as
105 a pivot, thus bringing the threaded ter-
minal portions 9 to any desired angle of
inclination.

The flanges 3 are adapted to support rail
engaging plates 10 each of which is bowed
transversely and extends beyond the curved
edge portions of the flanges 3. The edge of

the plate adjacent the rail to be secured has a longitudinal recess or rabbet 11 for receiving the edge portion of the base flange of the rail.

- 5 When it is desired to attach a rail to the tie, the bolts are placed at one side of the tie and in substantially horizontal positions, one end of each bolt being inserted through an opening 6 until the cylindrical intermediate portion 7 of the bolt is brought into said opening whereupon the bolt is swung upwardly with said central portion as a pivot and thus bringing the threaded extensions 9 above the flanges 3. A plate 10 is 10 placed on the threaded portions 9, said plate loosely engaging them, and the plate is then shifted along the tie until the rabbeted or grooved portion 11 thereof is brought into engagement with a base flange of a rail. 15 This sliding movement of the plates will result in the swinging movement of the bolts and after the plate has been properly positioned, nuts, such as indicated at 12, are screwed onto the threaded extensions 9 20 and against the plate, thus holding said plate against movement away from the rail. As has heretofore been stated the openings 6 are arranged in pairs and each opening is adapted to receive one bolt. The pair of 25 bolts thus located diverge upwardly, as shown in Fig. 2 and each one of the bolts engages separate rail engaging plates which are oppositely disposed and are adapted to engage opposite portions of the base flanges 30 of a rail. It will be apparent, therefore, that when the nuts 12 are tightened, the plates 10 will be shifted toward each other so as to tightly bind upon the rail and hold it against lateral displacement. Should it 35 be desired to shift the rail shown in Fig. 2 to the left, the nuts 12 upon the threaded terminals of the left bolt are loosened until the necessary movement of the rail to the left is permitted, after which the nuts on 40 the right-hand bolt are tightened so as to push the plate 10 which is under them, toward and into engagement with the rail. After the various parts have been tightened, the rail will be securely held in the position 45 to which it has been moved.

50 It is to be noted that the plates 10 are formed of resilient metal so that a certain amount of elasticity is obtained which insures the constant gripping of the rail and obviates all danger of stripping or breaking the bolts while the nuts are being tightened.

55 Instead of forming the tie body of a single piece of metal having oppositely extending top and base flanges, the said body 60 may be constructed as shown in Figs. 5 to 8 inclusive wherein two oppositely disposed channeled members are placed together to form the body, each of these members including a web 13, a base flange 14, and a 65 top flange 15, said base and top flanges hav-

ing their longitudinal edge portions curved toward each other to constitute means for anchoring a plastic filling between the flanges. The curved portions of the flanges have been indicated at 16 and the filling has 70 been illustrated at 17. The two sections of the tie body can be secured together in any manner desired and the webs 13 thereof have registering openings 18 corresponding with the openings 6 hereinbefore referred 75 to. In this form of tie the sections are preferably spread apart or bulged laterally at opposite sides of the rail supporting portions of the tie, and as indicated at 19, alining slots or openings 20 being thus produced 80 within the tie body and corresponding protuberances 22 being also produced at the sides of the tie. These bulged portions of the tie body are all coextensive and, as before stated, are arranged at opposite sides 85 of the rail supporting portions of the tie. They present broad bearing surfaces under which the road bed may be tamped, the intermediate portion of the tie being thus less firmly supported and therefore capable of 90 yielding to a slight extent to allow for desired resiliency of the tie. The projecting portions of the tie body also engage the road bed to a sufficient extent to prevent 95 the tie from creeping longitudinally. 95

As has heretofore been pointed out, the spaces between the top and base flanges of the ties are completely filled with plastic material except at those points where the bolts are located and, if desired, at the center of the tie, the plastic material being dispensed with at this central point so as to increase the elasticity of the tie.

100 It will be noted that the central cylindrical portion of each bolt is of greater diameter than its diverging arms 8, this being desirable because of the increase wear and strain upon this central portion. As each bolt extends through an opening in the web of the tie body and straddles a portion of 105 said web, the said bolts cannot become accidentally displaced unless the rail engaging plate 10 is entirely disengaged therefrom. Moreover the particular form of bolt shown transmits the strain directly to the center 110 of the body of the tie and distortion of any parts of the tie is thus prevented.

115 What is claimed is:—

120 1. A railway tie including a body having an apertured web, opposed rail fastening devices straddling the body and adjustable angularly relative to each other, and means carried by the terminals of the respective fastening devices for engaging opposite portions of a rail on the tie. 125

125 2. The combination with a metallic tie body having a transverse opening therein, of an angularly adjustable rail fastening member within the opening and straddling the body and a rail engaging device connected 130

- to the end portions of and adjustable with said member.
3. A railway tie including a body having a longitudinal web and longitudinal flanges along the top of the web, an angularly adjustable rail fastening member extending through the web and straddling said flanges, and means upon the terminals of said member for engaging one side portion of a rail.
- 10 4. A railway tie including a body having a web and longitudinally extending flanges along the top of the web, a rail fastening member mounted for rotation within and extending transversely of the web, said member including an intermediate bearing portion and diverging arms extending from said portion, and a device adjustably engaging and adjustable with the arms for engaging one side of a rail upon the tie.
- 15 5. The combination with a tie body having a transverse opening therein, of a member upon said tie for engaging one side portion of a rail, and a rail fastening member within the tie, said member including an intermediate portion mounted for rotation within the opening in the tie, and diverging means for adjustably engaging the said rail engaging member.
- 20 6. The combination with a tie having a transverse opening, and a rail engaging device upon the tie at one side of a rail, of a rail fastening element extending through the opening and adjustable angularly, said element having terminal portions engaging the rail engaging device.
- 25 7. The combination with a tie having a transverse opening, and a rail engaging device upon the tie at one side of a rail, of a fastening element within the opening and adjustable angularly, the terminals of said element engaging said device and means engaging said element for holding the rail engaging device in operative position.
- 30 8. The combination with a tie having
- transverse openings therein, and spaced devices upon the tie for engaging opposite portions respectively of a rail, of a fastening device detachably mounted within each opening and having spaced terminals detachably engaging one of said rail engaging devices, said fastening devices straddling portions of the tie and being separately adjustable angularly.
- 35 9. The combination with a tie having a transverse opening, and a rail engaging element upon the tie at one side of a rail, of a rail fastening device detachably mounted within the opening and adjustable angularly therein, said device having terminal portions detachably and adjustably engaging the rail engaging element.
- 40 10. A railway tie including an apertured web having longitudinal top flanges, rail engaging elements mounted on the flanges, and a rail fastening device detachably mounted within the aperture and adjustable angularly relative to the tie, said device including a central bearing portion, upwardly diverging arms, and terminals on the arms detachably and adjustably engaging said elements, said rail engaging device straddling the flanges.
- 45 11. The combination with a railway tie having a transverse opening, and resilient rail engaging elements on the tie, of a rail fastening device detachably mounted within the opening and adjustable angularly relative to the tie, said device straddling the flanges and detachably and adjustably engaging said elements.
- 50 80 In testimony that I claim the foregoing as my own, I have hereto affixed my signature in the presence of two witnesses.
